UNITED STATES PATENT OFFICE.

EDWIN J. YOUNG AND ALVIN D. WELKER, OF WADSWORTH, OHIO, ASSIGNEES TO THE
OHIO MATCH COMPANY, OF WADSWORTH, OHIO, A CORPORATION OF OHIO.

MACHINE FOR IMPREGNATING MATCH-STICKS.

Specification of Letters Patent. Patented Feb. 16, 1915.

1,129,032.

Application filed April 3, 1914. Serial No. 829,299.

To all whom it may concern:

Be it known that we, EDWIN J. YOUNG and ALVIN D. WELKER, citizens of the United States, residing at Wadsworth, in the county of Medina and State of Ohio, have invented a certain new and useful Improvement in Machines for Impregnating Match-Sticks, of which the following is a full, clear, and exact description.

10 The object of this invention is to provide means for the ready and effective impregnation of match sticks with a vehicle which will prevent after-glow and so reduce if not eliminate fire-danger in the careless handling of lighted matches.

15 The invention consists of mechanism for applying the impregnating material in the form of dust or fine powder, under conditions which will cause it to adhere to the sticks.

20 In the preferred construction this mechanism will form a part of a continuous match machine, in which the operations of cutting, sticking, impregnating, paraffining, dipping and drying are successively carried on, and we will so show and explain our invention herein, but without thereby limiting the invention to any particular machine or to a match machine.

25 30 In the accompanying drawings illustrating the invention, in the several figures of which like parts are similarly designated, Figure 1 is a transverse section and partial elevation, of our impregnating mechanism when forming part of a continuous match machine. Fig. 2 is a longitudinal section with the cover omitted. Figs. 3 and 4, 5 and 35 6, 7 and 8, and 9 and 10 are respectively elevations and edge views of four several forms of blades for circulating the impregnating material and insuring its application to the sticks.

When used in and as a part of a continuous match machine, the impregnating machine may utilize the side frames 1 of the machine for the reception of its component parts, and these side frames may be connected by four converging sloping walls, as shown in Figs. 1 and 2, so as to form a bin 2 to receive the impregnating vehicle in the form of finely divided powder or dust. A suitable impregnating material or vehicle is ammonium phosphate, reduced to an im-

55 is not limited to the use of any particular impregnating agent.

Inclined shafts 3 are arranged transversely of the frame within the bin, and these shafts are supported in suitable bearings 4 in the frame, and other bearings 5 in the bin, and on these shafts and turning with them are paddle wheels or agitators 6 which serve to stir up the material in the bin. These agitators are rotated from a power shaft 7 mounted in the frame and supplied with any suitable pulley or other power-receiving agent 8, and transmitting motion to the shafts 3 by any suitable means, such as bevel gears 9 and 10. Above the agitators are shafts 11 and 12, also arranged transversely of the machine, and having bearings in the side frames and arranged parallel one to the other. These shafts 11 and 12 are provided with blades 13 suitably spaced apart by washers 14. These blades 75 may be of any of a variety of different forms, some of which are illustrated in Figs. 3 to 10, the function of which blades is to throw the impregnating material upon the match sticks.

80 The shafts 11 and 12 are geared by toothed wheels 15 so as to turn in opposite directions, and they are rotated by means of a toothed wheel 16 on one of the shafts engaging a toothed wheel 17 on the power shaft. 85 These shafts 11 and 12 may also be given a slight longitudinal vibratory movement by means of wave cams 18 engaged by rollers 19 fixed to the side frames. The side frames are provided with ways 20 to receive and 90 guide the splint-carrier chains or plates 21 in which the match sticks 22 are stuck. These match sticks extend downwardly between adjacent blades 13, as indicated in Fig. 1.

95 23 is a cover (Fig. 1) arranged over the bin and the splint carrier to prevent the escape of the air and dust or powder from within the bin. Mounted upon the side frames are the hoppers 24 which extend down into the bin and serve as means for introducing the dust or powder within the bin. The bin having been supplied with the proper impregnating material, and the splint carrier supplied with match sticks, 100 and moved over the bin, the rotation of the agitators 6 will raise a cloud of dust or powder to the rotating blades 13 and these

will distribute the dust about the sticks with force enough to cause it to adhere to the sticks with sufficient tenacity to thoroughly impregnate the sticks, and without danger of the sticks losing the impregnating material in their further progress through the match machine, or their further treatment otherwise.

As already indicated, the blades 13 may be of a variety of forms. Referring to Figs. 3 and 4, the blade is shown in the form of a conventional Maltese cross, the opposite edges 25 of its arms 26 being drawn to a point, as indicated in the end view developed off of one arm above and to the left in Fig. 3, and also as shown in Fig. 4. As shown in Figs. 5 and 6 the blade may be made as a disk, with diagonally arranged holes 27. As shown in Figs. 7 and 8 the blade may be cruciform. In this case each arm 28 may have one of its edges 29 grooved and flared, and its opposite edge 30 beveled. As shown in Figs. 9 and 10 the blade may be a disk, provided with strips of bristles or fine wires 31 fastened thereon or therein, so as to project laterally preferably from both sides. In all of these forms of blades the tendency is to direct the current of dust against the rows of match sticks, and in addition the strips of bristles or fine wire shown in the construction illustrated in Figs. 9 and 10 will whip against the match sticks and tend to polish the match sticks. Furthermore, all of these various forms of blades effectively circulate the dust constantly and uniformly among the sticks as the sticks pass through the dust chamber and between the blades. The beveling of the arms of the blades as shown in Figs. 3 and 4 and the diagonal holes, shown in the blades of Figs. 5 and 6, and the flaring and beveling of the arms as shown in Figs. 7 and 8, and the lateral projection of the bristles or wires as shown in Figs. 9 and 10 insure the distribution of the dust against the match sticks, and as already stated, insure its constant circulation. If desired, and in order longer to expose the match sticks to the dust, the dust chamber above the bin may be extended 50 in front and rear of the bin as indicated in Fig. 2.

The operation of the machine has been sufficiently indicated in what precedes, and it is sufficient now to state that the impregnating powder is fed to the hoppers 24 and thence to the bin, where it is caught by the agitators 6 which in their rotation stir up the dust in a cloud-like form. This cloud of dust is then circulated between the depending match sticks 22 by means of the rapidly rotating blades 13, and by rotating the blades on opposite shafts toward one another the circulation of the dust is directed in such a manner that the dust will impinge directly on both the front and rear of the

match sticks as the sticks are moved through the machine and between the blades.

We have thus described one, and at this time the preferred, construction illustrating our invention, but esteem it as within our invention to modify the parts and their arrangement within the scope of the following claims.

What we claim is:—

1. A machine for impregnating match sticks, so as to render them non-glowing, comprising a bin, means to supply it with pulverulent impregnating material, rotary agitators arranged at or near the bottom of the bin, a pair of oppositely rotating shafts mounted above the agitators, distributing blades mounted on said pair of shafts and spaced apart thereon, and means to permit the conveying of the match sticks across the bin in ordered relation so that said sticks will pass between the spaced apart blades, said blades serving to direct currents of the impregnating material toward the sticks and cause such material to adhere to the sticks.

2. In a machine for impregnating match sticks, a bin, means to introduce the impregnating dust into said bin, rotary agitators arranged at or near the bottom of the bin, a pair of oppositely rotating shafts mounted above the agitators, distributing blades mounted on said pair of shafts and spaced apart thereon, and ways arranged above said pair of shafts and adapted to receive the match stick carrier so as to present the match sticks between the spaced-apart blades, said blades provided with means to direct currents of the impregnating dust toward the sticks and cause such dust to adhere to the sticks sufficiently to render them non-glowing.

3. In a machine for impregnating match sticks, a bin, means to introduce impregnating powder into said bin, rotary agitators arranged at or near the bottom of the bin, a pair of oppositely rotating shafts mounted above the agitators, distributing blades mounted on said pair of shafts and spaced apart thereon, said blades having powder-intercepting devices for directing currents of the powder against the match sticks, and ways arranged above said pair of shafts and adapted to receive the match stick carrier so as to present the match sticks between the spaced-apart blades.

4. In a machine for impregnating match sticks, a bin, means to introduce the impregnating material in powder form into said bin, rotary agitators arranged at or near the bottom of the bin, a pair of oppositely rotating shafts mounted above the agitators, distributing blades mounted on said pair of shafts and spaced apart thereon, said blades provided with laterally extending flexible projections intercepting currents of the powdered impregnating material and serv-

ing also to polish the match sticks, and ways arranged above said pair of shafts and adapted to receive the match stick carrier so as to present the match sticks between the spaced-apart blades.

5. In a machine for impregnating match sticks, a bin, means to introduce powdered impregnating material into said bin, rotary agitators arranged at or near the bottom of 10 the bin, a pair of oppositely rotating shafts mounted above the agitators, distributing blades mounted on said pair of shafts and spaced apart thereon, and ways arranged above said pair of shafts and adapted to receive the match stick carrier so as to present

the match sticks between the spaced apart blades, said blades provided with means to direct currents of the powdered impregnating material toward the sticks and cause it to adhere to the sticks sufficiently to render 20 them non-glowing, and means to vibrate the blade shafts longitudinally.

In testimony whereof we have hereunto set our hands this first day of April A. D. 1914.
